UNITED STATES PATENT OFFICE.

JOHN S. GOLDBERG, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,145,138.

Specification of Letters Patent.

Patented July 6, 1915.

Application filed March 9, 1911. Serial No. 613,362.

To all whom it may concern:

Be it known that I, JOHN S. GOLDBERG, a citizen of the United States, residing at Chicago, in the county of Cook and State of Illinois, have invented a certain new and useful Improvement in Carbureters, of which the following is a full, clear, concise, and exact description, reference being had to the accompanying drawings, forming a part 5 of this specification.

My invention relates to carbureters and its object is to provide a generally improved device.

To this end I contemplate numerous structural features which tend to the general 15 result of the provision of a simple effective device of few parts. These structural features are such that it may be said of my carbureter that it is built along the general 20 lines of a single axis, the various parts being nested one within another so that a compact arrangement is secured.

It is usual in the art at this time to provide carbureters with auxiliary air inlets which 25 come into play when and only when a sufficient suction has been created in the mixing chamber by the suction of the engine associated therewith. It is evident to those skilled in the art that this auxiliary air inlet 30 must be valve-controlled and that this valve must be automatic in its operation and it is in connection with this automatic valve that my invention provides distinctly new features of construction and operation.

It is significant in connection with my device 35 that but one air inlet is provided for the carbureter, the variations in the amount of air admitted to the mixing chamber being secured by changing the effective passageway 40 rather than by opening or closing a distinct and separate inlet. With this arrangement I am enabled also to secure effective starting of the engine, by the provision of a valve in the one air inlet, as will be described.

In connection with the air inlet control 45 mechanism I provide a new spring arrangement which is very effective in securing efficient operation, this arrangement eliminating entirely the undesirable chattering 50 which has been found so frequently in valves which are designed to respond to changes in the pressure in the mixing chamber. As a structural feature in this connection it will be noted that I use the very part which 55 defines the mixing zone for the constant air supply as the movable valve member which controls the existence and size of the supplemental air passage and, as will be evident to those skilled in the art, the result is a simple and economical structure.

Consistently with the other features of my invention I provide for the ready and convenient adjustment of the various parts and for the cleaning thereof, the latter feature being directed mainly toward the nozzle 60 from which the fuel is drawn.

My invention is embodied in the device 65 illustrated in the accompanying drawing, in which the figure is an axial sectional view of my carbureter.

The main structural supporting element 70 of my carbureter comprises two castings, one disposed above the other and held together in a manner to be described later. These two castings are noted in the drawings by the 75 reference characters 4 and 5, the latter resting upon the former and the gasket 6 of compressible material intervening so as to provide a tight joint.

The structural unit 4 comprises a shelf 80 7 and two circular concentric walls 8 and 9 extending upwardly therefrom, the former being provided with an extension in the form of a housing 10 which will be referred to later. The circular wall 9 forms the air 85 passage which extends downwardly through the shelf and which at the top leads into the mixing chamber 11. A double conical hollow member 12 is disposed inside the wall 9 and the top thereof rests upon the inwardly beveled edge 13 of the wall 9, which edge, as will be described later, constitutes a valve seat for the member 12. This member 12 is the "Venturi tube" which provides for the constant air supply and the 90 middle of which constitutes the zone in which the oil used as a fuel is sprayed. A fuel tube 13' is supported in axial relation to the circular wall 9 by means of a spider 14, 15, preferably integral with the tube and the wall as a single casting. The tube extends 95 downwardly below the shelf 7 and is formed for the reception of a rod or post 16 which is passed upwardly therethrough and is threaded at its end into a bridge 17 100 spanning the walls of the mixing chamber 11. The head of the post 16 engages the bottom of the tube 13' and it will be clear that the post forms a tie rod for holding the castings 4 and 5 together in the relation 110

2
shown. The top of the fuel tube 13' is beveled inwardly and a collar 18 which is passed down over the post 16 has a correspondingly formed surface resting thereon. 5 This surface is provided with a plurality of radial grooves 19, 19, through which, as will be described, the oil is drawn by the action of the engine. The Venturi tube 12, which has hereinbefore been referred to, is 10 provided with an internal spider which has the axial sleeve 20 through which the rod 16 passes, all as clearly illustrated in the figure. It will be clear that the Venturi tube has vertical movement and that this movement is effectively guided by means of the rod 16 and the sleeve 20.

The member 12 has secured thereto a downwardly extending rod 21 which passes through and is guided in an opening 22 in 20 the spider 14. This rod is screw-threaded at its end for the reception of a nut 24 and a helical spring 23 is disposed about the rod between this nut and the spider 14. This arrangement tends to hold the member 25 12 upon its seat 18 and the amount of tension which is exerted in this behalf can be adjusted by turning the nut 24 upon the rod in an obvious manner. The nut 24 is provided with a transverse saw-cut 28 which is adapted for the reception of a cotter pin 26 which may be inserted in a transverse opening in the rod. In this way the nut may be locked in any adjusted position. A helical spring 27 is disposed, 30 between the top of the collar 18 and the under side of the spider which connects the sleeve 20 with the tube 12. This spring tends to lift the tube 12 from its seat and therefore acts in opposition to the spring 35 23. It is thus seen that the valve formed by the tube 12 is balanced between the tension of the two springs and the operation will be hereinafter described.

The compartment between the circular 45 walls 8 and 9 provides a float chamber in which an annular float 28 is disposed. This float is attached to a swinging arm 29 which is pivotally mounted upon a pin 30 extending across the end of the housing 10. As 50 the float rises or lowers subject to the level of the oil contained in the float chamber, the swinging member 29 may respond by moving on its pivot. The member 29 is in the form of a yoke, and carries a stamping 35. 55 This stamping has a central opening through which a valve stem 33 extends, this valve stem having threaded engagement with the stamping. The stem 33 extends downwardly through an opening 36 in the casing and, 60 below this opening, is provided with a valve piece 37. The valve piece 37 is disposed in a valve chamber or pocket 38 which is closed by means of a plug 39 having threaded engagement with the casing. The plug 65 39 is provided with a pocket 40 and a heli-

cal spring 41 is disposed in this pocket and is extended up to the valve so that it may exert an upward pressure on the under side thereof. It is clear that the valve 37 controls the opening 36 and the stem is provided at its bottom end with a transverse slot for the reception of a screw driver which may be used after the plug 39 has been removed, to change the adjustment of the valve relative to the opening. The valve chamber 38 is connected by means of a passageway 42 with a pocket 43 in the casing which is internally screw-threaded for the reception of a union 44, this union being suitably connected with the supply pipe 45 which leads to the tank containing the oil to be used as a fuel. A straining screen 46 is provided in the pocket 43 so as to prevent solid impurities from clogging subsequent passages. The weight of the float 28 acts in opposition to the spring 41 and when it is in its lowered position it holds the valve 37 open so that fuel may enter from the supply tank by way of the passage 36. When considerable fuel has entered the float chamber, however, the float rises and this action, together with the spring, entirely, or at least nearly, closes the valve so as to cut off further supply for the time being. As the oil becomes depleted the float 95 drops and the passageway 36 is opened for the admission of more fuel.

The air passageway through the tube 9 is supplemented at the bottom by a horn 47 which is in the form of a horizontal pipe 100 with a vertical outlet. The fuel tube 13' passes downwardly through this vertical outlet and through a registering opening 48 in the bottom of the horn. The bottom of the fuel tube 13' is screw-threaded for the reception of a nut 49 which engages the bottom of the horn 47 and firmly clamps it to the under side of the shelf 7. The horn is provided with a gate valve 50 which is mounted upon a transverse shaft 51 and is provided with a notch 52 for a purpose to be described presently. The shaft 51 extends beyond the casing proper and is provided at its end with a double operating lever 53. This operating lever may be connected by suitable linkages with operating mechanism within the control of the person running the engine. The hub of the operating lever 53 is provided with a pair of notches 55, 55 in either of which a spring 111 pressed plunger 56, suitably mounted in the casing, may be disposed. This plunger will hold the gate valve in either of its two extreme positions with reasonable security so that it cannot be jarred or accidentally moved out of place. It will now be seen that the air comes in at the horn 47 and is there controlled by the gate valve 50. It then passes upwardly through the central passageway defined by the wall 9 and either 125 130

through the Venturi tube alone or both through and around it, depending upon the position of it relative to the valve seat 13. The air then proceeds up to the mixing chamber 11 and then passes on to the engine, the connection between the mixing chamber and the engine being controlled by a throttle valve 57 mounted upon a transverse shaft 58.

10 The float chamber is connected with the interior of the fuel tube 13' by means of the passageway 68, the passageway 69, and the restricted passageway 70. The last-named passageway is controlled by means of a needle valve 71, the stem of which has threaded 15 engagement with the casing and extends out beyond the same where it is provided with a finger piece 72. A stuffing gland 73 may be provided for obvious purposes. When it is desired to adjust the flow of oil from the 20 float chamber into the interior of the fuel chamber 13' the finger piece 72 may be manipulated in the desired direction so as to move the tapered end of the needle valve 25 toward or away from the opening 70. The wall 9 is provided with an enlargement 74 in the form of a vertical ridge and here a longitudinal passageway 75 is provided. This passageway connects with the float 30 chamber at the bottom and with the central air passage at the top near the valve seat 13.

When the Venturi tube 12 is down upon its seat it is evident that all the air passing into the mixing chamber must go through 35 the tube. The fuel nozzles 19 are disposed near the restricted area of the Venturi tube and as the air rushes upwardly through the tube in response to the suction formed by the operation of the engine, oil will be with- 40 drawn through the nozzles and volatilization will take place. When the suction created by the engine reaches a predetermined point the tension of the spring 23, which tends to hold the Venturi tube down on its seat, 45 is overcome and the Venturi tube is raised away from its seat. When it is in this position considerable air may rush through the annular supplemental passageway thus formed and the demands made by the engine 50 may be met. As before stated, the spring 27 tends to lift the valve from its seat and it is thus clear that this spring acts to assist the suction of the engine in this respect. When the spring 23 is compressed the spring 55 27 is extended and there is approximately no change in the tendency of the mechanical means to hold the valve in a definite position. In other words, the valve is balanced between the tension of the two springs, the 60 lower being stronger than the other so that the valve may be retained normally on its seat. However, as the tension of one of the springs increases, that of the other decreases and the amount of opposition to the 65 suction remains substantially if not quite

the same. This effectually removes the undesirable chattering which has been found to be so prevalent in prior art devices and permits a more accurate adjustment in the matter of the amount of tension which the 70 suction of the engine is required to overcome. When the Venturi tube 12 is lifted from its seat the oil passage 75 comes into play and the air rushing by the opening causes further fuel to be picked up. The 75 carbureter is also operative without the auxiliary air supply being accompanied by a corresponding fuel supply. The carbureter is operative by reason of the other fuel in- 80 lets alone.

When it is desired to start the engine it is necessary to have a rich mixture and in order to do this I provide means for concentrating most of the suction of the engine upon the fuel inlet while admitting only a 85 limited amount of air. This is secured by means of the gate valve 50 which, as before described, is provided with a restricted passage 52, and when the gate is closed, all the air which enters must enter by the re- 90 stricted passage 52. This action causes most of the suction to be concentrated upon the fuel inlet and comparatively little air is provided. The closing of the valve 50 causes a considerable reduction of pressure in the 95 air chamber below the automatic valve and the valve cannot be lifted from its seat by the suction in this starting action. Thus all the air entering the engine is confined to the restricted passageway around the fuel nozzle, causing a high aspirating effect with 100 comparatively little air in quantity and consequently a rich starting mixture.

I claim as new and desire to secure by Letters Patent:

1. In a carbureter, a mixing chamber, an air passage leading to said mixing chamber, a fuel nozzle in said passage, an auxiliary air inlet surrounded by a valve seat, a valve part controlling said auxiliary air inlet and 110 adapted to rest upon said seat, resilient means tending to raise said valve part from said seat, and stronger resilient means tending to hold said valve part upon said seat.

2. In a carbureter, a mixing chamber, an air tube extending downwardly from said mixing chamber and forming a valve seat at the top thereof, a spider extending across said air tube, a fuel tube carried by said spider and mounted in axial relation to said air tube, a movable tubular member normally resting upon the top of said air tube and surrounding part of said fuel tube, and a spring between said spider and an element carried by said tubular member for holding 120 said tubular member down on the top of said air tube.

3. In a carbureter, a casing having an air inlet, a mixture outlet for connection to an internal combustion engine, and a divided 130

- passage connecting said inlet and outlet, one branch of said passage being always open, a valve part for controlling the other branch of said passage, said valve part being responsive to the higher suctions of the engine with which the carbureter is connected, a throttle in said mixture outlet, a fuel-nozzle disposed exclusively in the first-named branch, and a manually-controlled valve in 5 said air inlet, said air inlet being otherwise unobstructed so that when the valve therein is open there will be substantially full atmospheric pressure exerted upon the underside of said valve part while the engine is 10 operating regardless of the position of the throttle.
4. In a carbureter, a casing having an air inlet, a mixture outlet for connection to an internal combustion engine, and a divided 15 passage connecting said inlet and said outlet, one branch of said passage being always open, a valve part responsive to engine suction controlling the other branch of said passage, a fuel nozzle disposed in the first-named branch, said fuel nozzle being subject 20 to the aspirating effect of the air passing through said first-named branch but not subject to the aspirating effect of the air passing through said second-named branch, a throttle in said mixture outlet, and a manually-controlled valve in 25 said air inlet, said air inlet being otherwise unobstructed so that when the valve therein is open there will be substantially full atmospheric pressure exerted upon the underside of said valve part while the engine is 30 operating regardless of the position of the throttle.
5. In a carbureter, a casing having an air inlet, a mixture outlet, and a divided 35 passage connecting said inlet and outlet, one branch of said passage being always open, a valve part for controlling the other branch of said passage, said valve part being responsive to the higher suctions of the engine with which the carbureter is connected, a throttle in said mixture outlet, a fuel-nozzle disposed exclusively in the first-named branch, and a manually-controlled valve in 40 said air inlet, said manually-controlled valve when in its closed position leaving a 45 passageway for a minimum admission of air.
6. In a carbureter, a casing having an air inlet, a mixture outlet for connection to an internal combustion engine, and a divided 50 passage connecting said inlet and outlet, one branch of said passage being always open, a valve part for controlling the other branch of said passage, a spring tending to hold 55 said valve part in closed position, said valve part being responsive against the tension of said spring to the higher suctions of the engine with which the carbureter is connected, a throttle in said mixture outlet, a fuel-nozzle disposed exclusively in the first-named branch, and a manually-controlled valve in 60 said air inlet, said air inlet being otherwise unobstructed so that when the valve therein is open there will be substantially full atmospheric pressure exerted upon the underside of said valve part while the engine is 65 operating regardless of the position of the throttle.

In witness whereof, I hereunto subscribe my name this 4th day of March, A. D. 1911.

JOHN S. GOLDBERG.
